E. F. HATHAWAY

SUSPENSION MEANS FOR TUBE FRAMES

Original Filed May 24, 1922

Inventor:
Edgar F. Hathaway
by Geo. N. Goddard, atty.

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

SUSPENSION MEANS FOR TUBE FRAMES.

Original application filed May 24, 1922, Serial No. 563,243. Divided and this application filed May 4, 1923. Serial No. 636,606.

To all whom it may concern:

Be it known that I, EDGAR F. HATHAWAY, a citizen of the United States, and resident of Wellesley, in the county of Norfolk and State of Massachusetts, have invented certain new and useful Improvements in Suspension Means for Tube Frames, of which the following is a specification.

This invention relates to tube frames for tuft weaving of pile fabrics such as Axminster carpets and is intended to improve the serviceability and durability of such tube frames. The present application is a continuation or division of an original application filed by me on the 24th day of May, 1922, 563,243, and is intended to cover one of the several forms of tube frame construction disclosed in that application and particularly illustrated in Figures 7 to 9 of the drawings forming part thereof.

As tube frames are suspended in large numbers from traveling carrier chains which carry them in a predetermined order to a position above the loom to be engaged by the transfer mechanism by which they are caused to deliver their tufts to the fabric being woven, they are subjected to numerous severe shocks and strains in the course of their travel to delivering position. Since it is necessary that the individual tuft tubes shall pass between the appropriate warp threads when delivering their tuft end, it is important that there should be no bending, breakage or displacement of the parts in order that the tube may be accurately gaged for proper positioning.

The present invention is intended to more fully satisfy the requirements by providing a construction which affords a very stiff, rigid and permanent arrangement of suspension means adapted to engage the carrier chains and constructed to afford means for accurately and reliably gaging or positioning the tube frame in relation to the transfer mechanism and capable of sustaining the repeated shocks to which the frames are subjected in service.

In the accomplishing of the above objects I have provided an improved means for rigidly and durably attaching the suspension hangers to the carrier bar of the tube frame, and have also made provision for preventing any angular displacement or transverse

displacement of these two members and have provided an improved construction and arrangement of chain-engaging hook that permits accurate and uniform gaging of the transfer devices against the relatively stationary or fixed portions of the suspension means. A further feature of the improvement consists in the provision of means for releasably locking the chain-engaging suspension hook in its outward or normal chain-engaging position while permitting the automatic release of said locking device in order to permit the hook to be disengaged from the chain for transfer to tuft delivery position in the loom.

These and other features of the invention will be particularly explained in the following specification and will be defined in the claims hereto annexed.

In the accompanying drawings I have shown a form of construction and arrangement illustrative of the principles of this invention, in which:

Figure 1 is an elevation of one end of a tube frame and spool chiefly in central section showing the suspension hook moved to inoperative or chain-releasing position to permit disengagement from or insertion into the carrier chain of the tube frame hanger.

Figure 2 is a similar view omitting the spool showing the suspension hook releasably locked in normal chain-engaging position.

Figure 3 is an end elevation of the suspension means as viewed from the outside.

Figure 4 is a similar elevation viewed from the opposite direction and showing the carrier bar in cross section.

In the practice of this invention, according to the form illustrated in the drawings, I employ a longitudinal tubular carrier bar *a* of rectangular cross section and across the end of this bar is secured a vertical hanger *21* of rigid construction sufficiently strong to resist bending or distortion under the strains of service, and provided at its upper end with a bearing boss or ear *7*, 100 to receive the journal of the usual yarn spool *d*. The rigid hanger element near its upper end at approximately the level of the bearing boss *7* is offset laterally and turned upward to form a link-penetrating or extension tongue *6*, which passes through

the opening in the appropriate link in order to position the tube frame on the chain *c* and cooperate with a suitable suspension hook for suspending the tube frame therefrom.

Instead of the usual flexible spring hook arm commonly employed in the art, I provide a vertical hook arm 20 of sufficient rigidity or stiffness to resist bending or distortion under service strains, and to secure the desired outward and inward movement the hook is fulcrumed at its lower end on a fulcral pin or axis 12 to allow it to have a pivotal or swinging movement outward, a coil spring 25 being suitably mounted to yieldingly press the upper end of the hook arm 20, which is formed in the shape of a hook 20^a outwardly into interlocking engagement with the carrier chain *c*.

In order to lock the yielding hook arm in its chain-engaging position I provide a pivoted dog or latch 22 which is mounted on a transverse pin 24 in a vertical slot of the hanger arm 21 to project through a registering slot 20^b in the hook arm so as to swing into position behind the inner face of the hook arm to lock the same in its outward position. The latch or locking member 22 is normally thrown outward by the action of a spring 23 coiled around its fulcral pin 24, and is so proportioned as to be engaged by the upper lip or lug of the usual transfer clutch member *b* when the clutch member moves inwardly to engage the tube frame for the purpose of disconnecting it from the frame and presenting the tuft-carrying tubes to the fabric in the loom, as shown in Figure 2. It will be understood that these transfer clutches or devices are of the usual construction having bottom, lateral and top wings forming at the opposite ends of the tube frame two carrier cradles having an inward movement to disengage the hook from the chain by contact and pressure and a downward movement for presenting the tube frame to the loom.

As it is important that there should be no longitudinal displacement of the tube frame in order that the appropriate warp-delivering tubes may pass between the appropriate warp threads and the fabric, I make provision for so arranging the hook arm that when it is pressed inward by the advancing transfer mechanism the outer face of its lower portion will lie flush with the outer face of the rigid or fixed hanger element 21 so that the transfer mechanism gages against the firm immovable hanger element 21, to position the tube frame preparatory to presenting it to the fabric instead of gaging against a yielding and movable hook. This flush relationship between the two elements of the suspension means is accomplished in this case by locating the fulcral axis of the hook inside of the outer

face of the fixed hanger and providing the hanger with an interior depression or recess which allows the adjacent vertical portion of the hook arm to swing thereinto so that when the transfer device *b* reaches the end of its inward movement it will gage against the firm immovable hanger element, thereby securing exact longitudinal position of the tube frame.

While the suspension hanger arm may be secured to the carrier bar in any suitable manner, I have illustrated in the drawings a novel and advantageous construction for accomplishing this purpose. The attaching means shown comprises a U-shaped bracket 80 having upper and lower parallel attaching wings 2 and 3 extending inward from the intermediate portion which is firmly secured to the main hanger element 21 by welding or otherwise.

A further advantage of the construction and arrangement permitting the hook to fold partly into the hook receiving recess in the suspension bracket when moved to chain releasing position is that the same carrier bar may be used with the thicker and more rigid suspension members, because such lateral infolding or telescoping of the two parts compensates for the extra thickness of the parts of the hanger and so change in length of carrier bar is required.

These attaching wings 2 and 3 are spaced so as to fit snugly against the top and bottom of the tubular carrier bar in telescopic or lapped relation thereto and are of the proper width to snugly fit between the front and back side walls of the carrier bar. Screws 4, serve to detachably secure the attaching wings to the carrier bar, but it is to be observed that the interlocking engagement between the attaching members or wings 2 and 3 and the top, bottom and side walls is such as of itself to prevent any angular or lateral displacement of the hanger in relation to the carrier bar thereby relieving the attaching screws of the principal shocks and strains to which this connection is subjected in actual service. This mode of attaching the suspension means to the carrier bar, therefore, affords a very reliable and durable construction which, in practice, insures against loosening the parts or disturbing the accurate relations desired.

In practice, when the tube frame is advanced by the carrier to position for transfer, the transfer mechanism moves inward, first engaging the latch or locking member 22 and turning that downward out of locking engagement with the inner face of the hook arm so as to allow the hook arm by the further inward traverse of the transfer mechanism to fold within the longitudinal recess in the fixed hanger 21 so as to allow the inwardly projecting portion of the transfer device to contact firmly against the outside 130

face of the fixed hanger somewhat below the level of its bearing lug and outwardly offset chain-engaging prong. This engagement or contact obtains also when the tube frame is being restored to the carrier chain after the tuft feeding operation and thus insures reliable positioning of the tube frame for once more properly registering with and penetrating the opening in its suspension chain link.

The U-shaped attaching bracket secured to the inside face of the hanger by projecting across the slot formed for the reception of the swinging hook arm serves to re-enforce the hanger at this point besides sustaining the annular and transverse strains upon the carrier bar connection.

What I claim is:

1. In a tube frame for weaving, the combination of a carrier bar, a chain-engaging vertical suspension hanger rigidly secured to the end of said bar, a cooperating hook arm pivotally mounted on said hanger and yieldingly pressed outwardly beyond said hanger to engage a carrier chain, said hanger and hook being arranged to permit the lower portion of the hook to lie substantially flush with the outside face of the adjacent portion of the hanger, substantially as described.

2. In a tube frame for weaving, the combination of a carrier bar, a vertical suspension hanger rigidly secured to the end of the carrier bar and provided with a spool journal-bearing at its upper end, said hanger being provided with an interiorly arranged recess, a chain-engaging hook arm fulcrumed about a pivotal axis lying inside the plane of the outside face of the adjacent portion of the hanger and arranged to be pressed inwardly by transfer mechanism toward the hanger against yielding resistance until the hook arm lies substantially flush with the adjacent face of the hanger whereby the transfer mechanism is allowed to gage against the face of said hanger when disengaging the hook from the chain, substantially as described.

3. In a tube frame for weaving, the combination with a longitudinal carrier bar, of a spool supporting suspension hanger comprising a bracket rigidly secured to the end of the carrier bar to project vertically therefrom, and a co-acting chain-engaging hook arm mounted on said bracket to swing outwardly therefrom under spring tension to releasably engage a carrier chain, said bracket being provided with a recess arranged to receive the opposed upwardly-extending portion of the hook arm when the latter is pressed inwardly by the transfer mechanism to release the hook-arm from engagement with said chain, substantially as described.

4. In a tube frame for weaving, the com-

bination of a vertical hanger rigidly secured to the end of the carrier bar, a cooperating chain-engaging hook arm mounted to lie outside of the vertical hanger when engaged with the chain and to be pressed inwardly, to lie partly in a longitudinal recess in the hanger when disengaged from the chain by transfer mechanism, substantially as described.

5. In a tube frame for weaving, the combination of a vertical hanger rigidly secured to the end of the carrier bar, a cooperating chain-engaging hook arm mounted to lie outside of the vertical hanger when engaged with the chain and to be pressed into flush relationship with the hanger when disengaged from the chain by transfer mechanism, and means for releasably locking the hook arm against accidental disengagement with the chain, substantially as described.

6. In a tube frame for weaving, the combination of a carrier bar, a vertical hanger rigidly secured to the end thereof, a chain-engaging hook fulcrumed on the hanger and normally pressed outward into suspension engagement with the chain, and a locking member arranged to automatically hold the hook in its outward position, said locking member being releasable from locking position by the tube-frame transferring mechanism when disengaging the hook from its carrier chain, substantially as described.

7. In a tube frame for weaving, the combination of a carrier bar, a vertical hanger arm secured thereto, a rigid chain-engaging hook arm pivotally mounted in the vertical hanger arm and normally pressed outwardly from the outside face of said hanger, and a spring latch mounted on the hanger arm in position to releasably retain the hook arm against inward displacement, substantially as described.

8. A suspension means for a tube frame embracing a rigid arm adapted to be secured to the carrier bar of the frame, a cooperating chain-engaging hook and a hook-retaining latch, both mounted on said arm in position to be released by the inward movement of the mechanism that transfers the tube frame from its carrier chain, substantially as described.

9. In a tube frame for weaving, the combination of a hollow carrier bar, a suspension hanger, a chain-engaging hook fulcrumed in the hanger, means for rigidly securing the hanger and the bar together, said means embracing a U-shaped bracket member secured to the inner face of said hanger with oppositely disposed parallel wings fitting snugly into the hollow end of the bar and forming torsion-preventing engagement with the side and bottom walls of the carrier bar, and fastening devices for securing the wings to the carrier bar, substantially as described.

10. In a tube frame for weaving, the combination of a longitudinal carrier bar, a hanger arm formed with an interior slot, a chain-engaging hook pivoted to swing into said slot, and means for attaching said hanger to the carrier bar embracing a U-shaped bracket secured to the hanger to bridge across said slot and having opposite parallel attaching means arranged and proportioned to form lapped engagement with the walls of said bar to prevent angular and transverse displacement, and fastening screws securing the wings and bar together whereby the slotted hanger is reinforced and the fastening screws are relieved of transverse and twisting strains, substantially as described. 15

In witness whereof, I have subscribed the above specification.

EDGAR F. HATHAWAY.
